UNITED STATES PATENT OFFICE.

JAMES T. HOGAN, OF JERSEY CITY, NEW JERSEY, ASSIGNOR TO THE NATIONAL MACHINE COMPANY, OF NEW YORK.

WORK-CLAMP FOR BUTTONHOLE-SEWING MACHINES.

SPECIFICATION forming part of Letters Patent No. 657,540, dated September 11, 1900.

Original application filed June 15, 1897, Serial No. 640,857. Divided and this application filed November 9, 1899. Serial No. 736,365. (No model.)

To all whom it may concern:

Be it known that I, JAMES T. HOGAN, a citizen of the United States, residing in Jersey City, in the county of Hudson and State of New Jersey, have invented a new and useful Work-Clamp for Sewing-Machines, of which the following is a specification.

I will describe a work-clamp embodying my invention and then point out the novel features thereof in a claim.

In the accompanying drawings, which form part of my application, Figure 1 is a vertical section taken lengthwise of the work-clamp top and bottom plates. Fig. 2 is an inverted 15 plan or bottom view of the top plate of the work-clamp. Fig. 3 is a top view of the bottom plate of the work-clamp. Fig. 4 is a view 20 similar to Fig. 1, illustrating a slight modification in the construction of the bottom plate of the work-clamp.

Similar letters of reference designate corresponding parts in all of the figures.

The work-clamp M comprises a top plate m' , having a shank portion m^2 and an enlarged 25 end portion m^3 , in which is formed a large rectangular opening m^4 . On the under side of the end portion m^3 are fastened two serrated bars m^5 , each being at or near its ends attached to or formed integral with resilient 30 arms m^6 , which are attached to the under side of the end portion m^3 of the top plate of the clamp. As here shown, the arms m^6 are formed integral with the cross-bars m^5 . Screws m^7 serve to fasten the arms m^6 to the top plate 35 of the clamp. The arms m^6 of each bar m^5 cross the other bar m^5 , and their resilience is such as to move the serrated bars downwardly with reference to the top plate of the clamp. Hence when the serrated bars meet with any 40 considerable resistance the arms m^6 will be deflected upwardly, and thus will impart to the serrated bars a movement away from each other. This movement will have the effect of spreading the fabric in the clamp. The 45 large rectangular opening in the top plate of the clamp gives the operator an opportunity to see the serrated bars and the fabric beneath them.

The bottom plate of the clamp has a shank portion m^8 and an enlarged end portion m^9 . In the top of the latter is a recess m^{10} , which is made in the shape of an arc of a cylinder and is provided along its central line with a slot m^{11} . The serrated bars m^5 coact with the bottom of this recess close to the sides of its slot. The recess m^{10} , instead of being made in the shape of an arc of a cylinder, may be provided with a shoulder m^{12} for coacting with the serrated bars m^5 to make a more positive engagement of the fabric with the clamp.

The shank portion of the bottom plate is fastened to a bar m^{13} , which bar may be attached to a suitable feed mechanism, such as shown and described in my application, Serial No. 640,857, filed June 15, 1897, of which the present application is a division. To the bar m^{13} is hinged a lever m^{14} , which at its free end carries the shank portion m^2 of the top plate m' . A stud m^{15} rises from the bar m^{13} through a hole in the lever m^{14} and has pivoted to its upper end a cam-lever m^{16} , which serves to adjust the lever m^{14} , so that it will depress the top plate of the work-clamp or permit it to rise. A spring T, surrounding the stud m^{15} and bearing at its upper end against the lever m^{14} , raises the latter and the plate m' when the cam-lever m^{16} is moved to release the lever m^{14} .

What I claim, and desire to secure by Letters Patent, is—

A sewing-machine work-clamp comprising a plate having an opening therein, two serrated bars crossing such opening, each of said serrated bars having at the ends resilient supporting-arms extending across the line of the other serrated bar, substantially as specified.

In testimony whereof I have signed my name to this specification in the presence of two subscribing witnesses.

JAMES T. HOGAN.
